US0D1064700S

(12) **United States Design Patent** (10) **Patent No.:** **US D1,064,700 S**
(45) **Date of Patent:** **** Mar. 4, 2025**

(54) **STRAW COVER**

(71) Applicant: **Shenzhen Yuluo Technology Co., Ltd.**,
Shenzhen (CN)

(72) Inventor: **Xiyang Zhao**, Shenzhen (CN)

(73) Assignee: **Shenzhen Yuluo Technology Co., Ltd.**,
Shenzhen (CN)

(*) Notice: Patent file contains an affidavit/declaration
under 37 CFR 1.130(b).

(**) Term: **15 Years**

(21) Appl. No.: **29/923,410**

(22) Filed: **Dec. 29, 2023**

(51) LOC (15) Cl. **07-06**

(52) U.S. Cl.

USPC **D7/300.2; D7/510**

(58) **Field of Classification Search**

USPC D7/213, 387, 392, 391, 507, 514, 515,
D7/300.2, 900; D19/194

CPC A45F 2200/0583

CLAIM

The ornamental design for a straw cover, as shown and described.

DESCRIPTION

FIG. 1 is a front perspective view of a straw cover, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions of the straw cover shown in broken line form no part of the claimed design.

1 Claim, 8 Drawing Sheets
